UNITED STATES PATENT OFFICE.

GEORGE H. POOR, OF ST. LOUIS, MISSOURI, ASSIGNOR TO THE AMERICAN BRAKE COMPANY, OF SAME PLACE.

DRAW-BAR FOR CARS.

SPECIFICATION forming part of Letters Patent No. 341,601, dated May 11, 1886.

Application filed January 20, 1886. Serial No. 189,189. (No model.)

To all whom it may concern:

Be it known that I, GEORGE H. POOR, a citizen of the United States, residing at St. Louis, in the State of Missouri, have invented 5 certain new and useful Improvements in Draw-Bars for Cars; and I hereby declare the following to be a full, clear, and exact description of the same, reference being had to the accompanying drawings, illustrating the application of said invention, wherein—

Figure 1 is a plan view of a strap draw-bar embodying my invention. Fig. 2 is a vertical longitudinal section of the same. Fig. 3 is a plan, and Fig. 4 a vertical longitudinal 15 section, of a stem draw-bar having my invention applied thereto. Figs. 5 and 6 are modified forms of single and double springs, whereby the same results may be obtained. Fig. 7 shows another modification.

Like letters refer to like parts wherever they occur.

In order that the objects and advantages of the present invention may hereinafter more fully appear, as well as its characteristic features, it will be necessary, first, to briefly recite the present state of the art and its attendant disadvantages and objectionable features.

The present prevailing draw-bars throughout the United States are the movable strap-and-stem draw-bars, wherein the movement of the bar is resisted by two or more draw-springs of equal length and power, confined between two follower-plates, having limited 35 movement in draw-bar guides secured to the draw-bar timbers of the bed; and these draw-bars must also have the functions of buffers, as independent buffers are not desirable or generally admissible. The power or resistance of these draw-springs has heretofore been 40 adapted and graded to the capacity of the car and has been uniform throughout. As a result of this construction springs which were sufficiently powerful to give the required ultimate 45 resistance to the push or pull on a loaded car lacked the elasticity and quick action necessary to meet sudden strains or jars, while springs having the elasticity to meet sudden jars or strains lacked the ultimate resistance required for heavy loads. So

long as cars of low capacity—say twenty thousand pounds or twenty-five thousand pounds—met the demands of traffic the present form of draw-bar has sufficiently well met the requirements, because with great care it has 55 been possible within practical limits to regulate the force or power of the springs, by using a number of springs to obtain the necessary ultimate resistance with a practicable amount of resiliency or elasticity, so as to 60 keep the loss of springs, strain, breakage of links, and wear and tear within due bounds; but this rigidity or slow initial yield of the springs has had its disadvantages in many respects: First, in starting and stopping loaded 65 trains the engine and brakes have had to meet and overcome the dead weight or inertia of the whole train, and not the individual weight of the several cars and gradual accumulation, as would be measurably the case if 70 the draw-bar spring yielded under low pressure first, instead of rapidly setting or closing to its ultimate point of resistance, as it now does, so as to make what may be termed a “dead” or “rigid” pull or push from the start; 75 secondly, this rigid pull or dead weight results in the frequent breaking of links and pins, destruction of springs and draw-bars generally, racking of draw-bar timbers and car-beds, and many other objectionable features, which will be readily apparent to the railroad manager and need not be enumerated here; thirdly, this rigidity, dead weight, or inertia of the train has compelled the use of 80 more powerful locomotives and prevented the economical use of what is termed “close coupling,” such as the “Janney” and like couplings; finally, now that the demand for cars of forty thousand pounds to sixty thousand pounds capacity is increasing, the problem 85 can no longer be solved by multiplying the number of draw-springs, as will be apparent to all railroad men.

The object of the present invention is, therefore, to overcome the several objections and 90 disadvantages hereinbefore referred to, and provide a movable draw-bar and buffer, which, while possessing all the power which can possibly be demanded, will also possess quick initial elasticity or resilience, so as to meet all sud- 95

den jars, strains, or shocks without breakage or derangement, and yet shall be as simple, durable, efficient, and compact as the present construction.

5 I will now proceed to describe more specifically the best means now known to me of carrying out my invention.

In the drawings, A indicates the draw-timbers; B, the draw-bar guides secured thereto; C, the stops for arresting and limiting the movement of the follower-plates; D D', the follower-plates; E, the draw-bar, with which may be used the strap F or the stem or bolt G, as preferred, and all of which may be as shown or of any equivalent or well-known construction.

H H' indicate the draw-springs, which may occupy their usual position in the combination; but in lieu of being the usual form I employ a graduated spring, which may be of any desired construction. For purposes of illustration three methods of securing this end have been shown. Two helical springs of unequal length may be employed, nested, one 25 within the other, preferably the shorter within the longer.

I have obtained good results from a spring of the following dimensions, viz: an outer 30 spring, H, coiled from one (1) inch material, diameter of coil six (6) inches, length of spring eight and one-quarter (8 $\frac{1}{4}$) inches; an inner spring, H', coiled from three-quarter ($\frac{3}{4}$) inch material, diameter of coil four (4) inches, length of spring seven and one-quarter (7 $\frac{1}{4}$) inches, the outer spring graduated to set to the length of the shorter spring under four thousand pounds pressure, the united springs 35 adapted to afford an ultimate resistance of eight (8) tons. The above proportions are given simply as a matter of illustration, and not for purposes of limitation, as the springs will necessarily vary as to ultimate power of 40 resistance, according to capacity of the car.

Another manner of accomplishing the same 45 result is shown in Figs. 5 and 6, wherein one or more helical springs are employed, said springs coiled from a bar or rod whose greatest portion—say middle half or two-thirds—is of 50 a diameter adapted to produce a spring whose power shall equal the greatest ultimate resistance desired, while its ends are reduced (preferably tapered) to a diameter which will produce a coiled spring of the least resistance, by which means a graduated draw-spring can be 55 obtained of great initial elasticity combined with great ultimate power, substantially as hereinbefore set forth.

A third manner of accomplishing the same

result, and one naturally suggested by Figs. 1 and 2, is that shown in Fig. 7—viz., the duplication of the follower-plates and the interposition of light quick-acting springs e between the follower-plates at each end.

If desired, three or more helical springs of different lengths may be nested as easily as 65 two, and without further invention; but as no result other than a graduated spring of the character shown in Figs. 1 and 2 would be obtained, it has not been deemed necessary to illustrate it. It is also evident that in the 70 modified spring, Figs. 5 and 6, the central quarter or third of the bar may be of least diameter, so as to grade the spring at the center rather than at the ends.

The advantages are, as hereinbefore specified: A quick initial action of the draw-bar is obtained which will almost, if not entirely, avoid the breaking of links, pins, &c., permit the economical use of close couplers, facilitate the starting and stopping of trains, and 80 the draw-bar can be adapted as to power to cars of any capacity with as great ease and as cheaply and simply as draw-bars of the present form.

I am aware that heretofore a rod having a 85 piston or single follower at the rear end of the rod and two or more springs of different lengths have been combined to form a pull-rod for cars, and that in conjunction with cars having such a pull-rod buffers having a piston, a cylinder, and a confined nest of springs of unequal lengths have also been employed, and do not herein claim such devices, as the pull-rod cannot perform the function of a buffer nor the buffer perform the function of a 95 pull-rod, and the two cannot be used advantageously on cars as constructed in this country. Therefore,

Having thus set forth the nature, operation, and advantages of my invention, what I 100 claim, and desire to secure by Letters Patent, is—

In a combined draw-bar and buffer, the combination, with the movable draw-head and its two follower-plates, of a graduated spring 105 or springs interposed between the follower-plates, so as to be compressed when the draw-head moves in either direction, substantially as and for the purposes specified.

In testimony whereof I affix my signature, in 110 presence of two witnesses, this 2d day of January, 1886.

GEORGE H. POOR.
